UNITED STATES PATENT OFFICE

170,709

ELECTRIC MOTOR

Henry E. Lund, Racine, Wis.

Application April 30, 1953, Serial No. 24,774

Term of patent 3½ years

(Cl. D26—5)

To all whom it may concern:

Be it known that I, Henry E. Lund, a citizen of the United States, residing at Racine, in the county of Racine and State of Wisconsin, have invented a new, original, and ornamental Design for an Electric Motor, of which the following is a specification, reference being had to the accompanying drawing, forming part thereof.

In the drawing:

Fig. 1 is a front elevational view of an electric motor showing my new design with the shaft partially broken away for the convenience of illustration;

Fig. 2 is a top view thereof;

Fig. 3 is an elevational view looking at one end of the motor; and

Fig. 4 is an elevational view looking at the opposite end of the motor.

I claim:

The ornamental design for an electric motor, substantially as shown.

HENRY E. LUND.
